YARN HOLDER

Application filed September 5, 1931. Serial No. 561,401.

This invention relates to yarn holders or transfer combs employed to retain the ends of a series of yarns wound upon a spool in the desired relation to each other.

Yarn holders of the type to which the present invention relates are extensively used in connection with the spools for tube frames, and serve to hold the ends of the different colored yarns wound upon a spool in place as the spool is taken from the spooling machine and transferred to the threading machine employed to draw the yarns through the tubes of a tube frame.

In preparing tube frames for use upon Axminster looms a series of yarns are wound upon spools in accordance with a prearranged pattern. The spools are then presented to tube frames and the yarns are drawn through the individual tubes of the tube frames ready to be inserted in a fabric as pile tufts in the subsequent weaving operation.

It is essential that the yarns wound upon a spool in accordance with a predetermined pattern have the cut ends held in their proper relation to each other, so that in the subsequent threading operation they will be drawn through the tubes of the tube frames in the proper order.

It is therefore the common practice to use a yarn holder or transfer comb to hold the yarn ends side by side in their proper relation from the time a spool leaves the spooling machine until it is presented to the threading machine and the yarns are drawn into the tubes of a tube frame.

These yarn holders as commonly constituted, comprise a comb having teeth between which the yarns are introduced, and a cover or cap that fits over the ends of the teeth to prevent the yarns from escaping. The comb is readily formed of a strip of sheet metal, having a length corresponding to the length of the spool with which it is to be used, and the cover is commonly formed of a metal

strip U-shaped, in cross section to fit over the teeth of the comb.

It is important that the cover or cap be locked in place upon a comb while the comb is associated with a spool to hold the yarn ends in place, and several forms of spring clips have been proposed heretofore for removably fastening a cover to a comb, but these fastening devices as constructed heretofore have been more or less difficult to interengage and release. They are also open to the objection that they frequently become bent or broken while in use or in storage and necessitate a considerable expense for repairs. The breakage of these prior fastening devices has also been due largely to the fact that they are provided with projecting portions that extend beyond the comb or cover in an unprotected condition.

The present invention relates to yarn holders or transfer combs provided with novel means for removably locking the cover to the comb, the arrangement being such that no portion of the locking means protrudes from the comb or cover and as a result they are well protected from injury.

A more specific feature of the invention consists of locking means comprising cooperating pins and notches, the construction being such that the parts are simple, strong and durable and are extremely easy to engage and disengage, and a further feature resides in spring means for preventing accidental movement of the parts in a direction to release a pin from its notch.

Other features of the invention and novel arrangement of parts, in addition to the above, will be hereinafter described in connection with the accompanying drawings which illustrate one good practical form of the invention.

In the drawings:

Fig. 1 is a side elevation showing the relation of the vertically movable comb holder to the spooling machine;

Fig. 2 is a sectional elevation showing the comb and holder elevated;

Fig. 3 is a side elevation of a yarn holder provided with the interlocking means of the present invention;

Fig. 4 is an end view of the parts shown in Fig. 3;

Fig. 5 on an enlarged scale is a side elevation with parts broken away of the left hand end of the yarn holder of Fig. 3;

Fig. 6 is a similar view of the right hand end of the yarn holder of Fig. 3;

Fig. 7 is a perspective view of the left hand end of the yarn holder, the cover being shown in spaced relation to the comb; and

Fig. 8 is a sectional view of the cover provided with a modified construction.

In preparing spools for use in tube frames the spools are commonly wound on spooling machines. These machines are provided with a creel or other means for supporting a large number of spools 10 provided with different colored yarns α adapted to be wound on a spool 11 in accordance with the pattern requirements of the row of tufts to be presented to the fabric by the spool. The spool 11 is conveniently driven during the winding operation by mounting it between the pair of lower rolls 12 and the upper floating roll 13, and the yarns as they are delivered to the spool 11 may be guided by the usual reed 14 having the upwardly extending pegs 15. The reed 14 is conveniently supported by the spaced brackets 16.

During the winding operation illustrated in Fig. 1 of the drawings, the comb 17 of the yarn holder is preferably supported below the series of yarns α in position to be moved into engagement with the yarns, and the means shown to this end consists of a transversely extending bar 19, which is supported adjacent the opposite sides of the spooling machine by the racks 20 slidably supported in brackets 16. The teeth of these racks mesh with the teeth of the gears 21 secured to the transversely extending shaft 22 which may be rotated by the crank handle 23. The upper edge of the transversely extending bar 19 may be provided with a groove adapted to receive the comb 17 and hold the teeth in an upright position.

As soon as the desired amount of yarn has been wound upon the spool 11 the crank handle 23 may be rotated to elevate the racks 20 and combs 17 so as to introduce the teeth of the comb between the adjacent yarns α , as shown in Fig. 2. The comb cover or cap 24 may then be placed over the teeth of the comb and secured to the comb by means to be described. The yarns α are then cut adjacent the yarn holder, whereupon this holder or transfer comb may be tried or otherwise secured to the wound spool 11, whereupon the spool may be placed in storage for future use or may be conveyed direct to a threading ma-

chine, not shown, but adapted to draw the yarns α through the individual tubes of a tube frame.

The winding machine above briefly described forms no essential part of the present invention but has been illustrated and described to make clear the field of use of the yarn holder or transfer comb embodying the features of the present invention.

The comb 17, as shown, may be formed of a flat metal strip having the lower edge portion folded upwardly, as at 25, to give stiffness to the metal strip and at each end of the comb are provided the end portions 26 and 27, which serve to protect the teeth of the comb. The cap 24, as illustrated, comprises a strip conveniently formed of metal U-shaped in cross section to fit over the teeth 18 of the comb. The arrangement in the construction shown is such that the cap 24 does not clamp the yarn α between the teeth of the comb, but prevents the yarn from escaping between the teeth by a lateral movement, while the yarn may be drawn from between the teeth to facilitate the operation of drawing the yarn into the tubes of the tube frame.

The construction of the yarn holder or transfer comb so far described has been employed heretofore and constitutes one form of yarn holder with which the means of the present invention for removably locking the cover to the comb may be associated. It is to be understood, however, that the features of the present invention may be employed in connection with other types of yarn holders than herein illustrated and that the locking means of the present invention may be given various embodiments other than that shown.

In accordance with the particular embodiment of the invention illustrated, one protecting end portion of the comb 17, for example the left end portion 26 is provided with a relatively deep notch 28 adapted to receive a locking device 29, extending transversely between the spaced side walls of the cover 24. The opposite end portion 27 of the comb is shown as provided with a notch 30, of less depth than the notch 28, and the right hand end of the cover 24 is provided with a transversely extending locking device 31. After the locking device 29 has been placed within the notch 28, as above described, the locking device 31 is readily engaged with its notch 30 by moving the cover to the left to present the locking device 31 for engagement with the notch 30.

The locking devices 29 and 31 carried by the cover, and as shown by Figs. 3 to 7 inclusive, are constituted as pins bridging the space between the side members of the cover above the lower edges of the side portions.

In accordance with the present invention means is provided to prevent accidental retrograde movement of the cover 24 once it

has been assembled on the comb with the locking devices engaged with their cooperating locking notches, with the important result that the spaced yarns in the comb will be held 5 from disengagement therefrom until intentionally released. As a simple and convenient means to this end a yielding member, such, for instance as a spring 32, is caused to act upon the cover and urge it to its final locked 10 position.

The spring 32 may be variously constructed and is conveniently mounted in the channel provided between the lower portion of the comb and the spaced up-turned portion 25, 15 where it may be supported by a pivot pin 33 extending through a looped portion of the spring. The upwardly extending portion of the spring 32 preferably projects between and is protected by the side portions of the cover, 20 and as shown is held in position to act against the pin 29 by the laterally extending tail portion 34, which may be retained in the position shown by a portion 35 of the comb turned inwardly over the end of the tail 34.

25 It will be seen from the foregoing that the means of the present invention for removably locking the cover to the comb are so constituted as to insure proper relation of parts for the purpose stated and present no protruding parts which extend beyond the comb or its cover, a condition which greatly reduces the likelihood of the interlocking parts being injured. It is further apparent that the parts may be readily moved to and from their interlocked position by simply moving the 30 cover 24 lengthwise of the comb 17. The engagement of the pins 29 and 31 with their respective notches 28 and 30 may be further facilitated by providing adjacent each notch 35 the inclined portion 36 adapted to guide the pin downwardly into this notch.

While in the preferred embodiment of the invention shown and described the pins 29, 31 and 33 have been illustrated as bridging 40 the space between the walls of the cover or comb, it will be apparent that the desired result may be secured by forming these parts as an integral portion of the cover or comb by simply bending or distorting portions of 45 the sheet metal inwardly in the modified construction of Fig. 8, wherein the locking device 37 is formed by forcing a small portion of each wall of the cover inwardly.

The means of the present invention for 50 locking a cover to its comb are simple, strong and durable, and since all the parts are protected and do not project from either the comb or cover, the chances of these parts being injured while the yarn holders are in 55 use or in storage are practically eliminated.

60 What is claimed is:—

1. A yarn holder or spacer for the end portions of a series of yarns wound upon a spool, comprising, in combination, a comb member 65 having a series of teeth for directing the

yarns in spaced relation, a cover member for the teeth of the comb, and interengaging locking devices at each end of said members inclosed and housed by the cover member to protect the locking devices from contact with 70 extraneous objects when the comb and cover members are in locked relation.

2. A yarn holder or spacer for the end portions of a series of yarns wound upon a spool, comprising, in combination, a comb member having a series of teeth for directing the yarns in spaced relation, a cover member for the teeth of the comb, interengaging locking devices at each end of said members comprising projections on one and notches on the other inclosed and housed by one of the members to protect the locking devices from contact with extraneous objects during 75 storage and use, and means for obstructing relative longitudinal movement of said members from their locked relation.

3. A yarn holder or spacer for the end portions of a series of yarns wound upon a spool, comprising, in combination, a comb member having a series of teeth for directing the yarns in spaced relation, a cover member for the teeth of the comb, locking devices at each end of one of said members, and locking notches at each end of the other member engageable by the locking devices by relative longitudinal movement of said members, the said locking devices and locking notches being inclosed and housed by the cover member to prevent contact with extraneous objects 80 during storage and use, and spring means normally acting in a direction longitudinally of said members to hold the locking devices 85 and notches in locked relation.

4. A yarn holder or spacer for the end portions of a series of yarns wound upon a spool, comprising, in combination, a comb member having a series of teeth for directing the yarns in spaced relation, a cover member for the teeth of the comb, locking devices at each 90 end of said members contained within and housed by the cover member to prevent contact of any part of the locking devices with extraneous objects during storage and use.

5. A yarn holder for the end portions of a series of yarns wound upon a spool, comprising a comb member having a series of teeth for directing the yarns in spaced relation, a cover member for the teeth of the comb, fixed locking pins extending transversely at each end of the cover member, locking notches of different depths, one at each end of the other member, that the locking devices and notches may interlock by relative longitudinal movement of said members first in one and then in the opposite direction.

6. A yarn holder for the end portions of a series of yarns wound upon a spool, comprising a comb member having a series of teeth for directing the yarns in spaced relation, a cover member for the teeth of the comb,

locking devices between the cover and comb that are entirely inclosed or housed by the cover member when the two members are in locked relation to protect the locking devices from contact with extraneous objects, and a spring inclosed by the cover member to hold the two members in locked relation.

7. A yarn holder for the ends of a series of yarns wound upon a spool, comprising a comb or spacer having teeth to hold the yarns in spaced relation, a cover of U-shaped cross section for the teeth of the comb or spacer, a locking device at each end of the cover bridging the space between the side walls thereof, a protector at each end of the comb adapted to enter the space of the cover between the side walls thereof and each provided with a notch for engagement by the locking devices bridging the space between the side walls of the cover, so that no portion of the locking devices project beyond the comb or cover when in locked relation.

8. A yarn holder for the ends of a series of yarns wound upon a spool, comprising a comb or spacer having teeth to hold the yarns in spaced relation, a cover of U-shaped cross section for the teeth of the comb or spacer, a locking device at each end of the cover bridging the space between the side walls thereof, a protector at each end of the comb adapted to enter the space of the cover between the side walls thereof and each provided with a notch for engagement by the locking devices bridging the space between the side walls of the cover and a spring carried by the comb and extending into the space between the side walls of the cover to act upon the cover and hold it in locked position so that no portion of the locking devices project beyond the comb or cover when in locked relation.

9. A yarn holder for the ends of a series of yarns wound upon a spool, comprising a comb, a cover of U-shaped cross section for the teeth of the comb, a locking device at each end of the cover bridging the space between the side walls thereof, a protector at each end of the comb to enter the space between the side walls of the cover, and each provided with a locking notch, one of which is of greater depth than the other that the locking devices may be interengaged by relative longitudinal movement of the comb and cover, and inclined guides on the protectors for directing the locking devices into locking engagement with their cooperating notches.

10. A yarn holder for the ends of a series of yarns wound upon a spool, comprising a comb, a cover of U-shaped cross section for the teeth of the comb, a locking device at each end of the cover bridging the space between the side walls thereof, a protector at each end of the comb to enter the space between the side walls of the cover, and each provided with a locking notch, one of which

is of greater depth than the other that the locking devices may be interengaged by relative longitudinal movement of the comb and cover, and inclined guides on the protectors for directing the locking devices into locking engagement with their cooperating notches, and means for yieldingly holding the locking devices and notches in locked position.

In testimony whereof, I have signed my name to this specification.
